R. S. PEELLE

ELECTRIC INTERLOCK FOR ELEVATOR DOORS

Filed April 10, 1925

Robert S. Pulle INVENTOR

BY
Frank J. Wainwright
ATTORNEY.

UNITED STATES PATENT OFFICE.

ROBERT S. PEELLE, OF HOLLIS, NEW YORK, ASSIGNOR TO THE PEELLE COMPANY, OF BROOKLYN, NEW YORK, A CORPORATION OF NEW YORK.

ELECTRIC INTERLOCK FOR ELEVATOR DOORS.

Application filed April 10, 1925. Serial No. 22,188.

My invention relates to electric interlocks for elevator doors, and more particularly to a construction of lock by which its assembly in the elevator door installation will be facilitated, and the effectiveness of the lock in co-ordinating the control of the current to the motor for actuating the elevator with the movements of the elevator doors at any floor, will be made highly effective.

It is a common requirement of building departments of different communities that elevator doors, particularly those used in warehouses, be equipped with what is known as an electric interlock by which the application of power to the motor for operating the elevator is so controlled that the car may be operated only when the doors of all of the floors of a building are closed. In securing the desired result it has long been the practice to provide switch mechanisms arranged in the circuit to the motor and controlled by a member carried by the door, so that upon any door being opened, the switch mechanism will also be opened to interrupt the circuit to the elevator motor and will remain open until the door has been again closed.

The various switch mechanisms adjacent all of the doors of one vertical series have been arranged in electrical series with each other and with the elevator motor, thus permitting the circuit to the motor to be controlled by the movements of the door at any floor.

When making the elevator door installation which includes the electric interlocks, great difficulty has heretofore been experienced in wiring the interlock system, and the construction of the interlock has been such that there has been present a certain factor of uncertainty in its operation, since while the closing of the circuit resulted from a positive movement of the locking mechanisms of the door, the opening of the circuit, although controlled by the elevator door lock mechanism, was permitted and not positively caused by such movement.

Experience has shown that it is not uncommon for operators to destroy the efficiency of the electric interlock system by blocking a switch mechanism in such a way as to prevent the interruption of the circuit with the opening of a door, thus destroying the safety factor designed to be introduced in elevator door installations by

the use of such electric interlocks. With the above conditions in mind, I have produced an electrical interlock for use in combination with elevator doors of the so-called counterbalanced or analogous types of doors, wherein each switch mechanism may be firmly supported from the rail structure for the elevator doors in operative relation to the co-operating locking mechanism upon the doors for controlling same, so that a violent opening and closing movement of the doors cannot disarrange any of the parts of the switch mechanism, or any of the electrical connections therein. The construction is also such as to permit ready access to all parts of the switch mechanism during the installation of the electric interlock system, while preventing interference with the switch mechanism by the elevator operator in a manner which would tend to prevent the opening of the circuit simultaneously with the initial opening of the door.

While the construction of the switch mechanism proper is such as to cause the automatic actuation of the switch arm carrying a movable contact, I so construct this arm and the co-operating member of the lock mechanism carried by the door, that this automatic feature may be relied upon solely to maintain the contacts separated, the initial separation of these contacts being positively effected upon the operation of the door lock mechanism, and thus ensure not only against a possible failure of the interruption of the circuit with the release of the lock mechanism preparatory to the opening of a door but the blocking of the switch arm and the switch mechanism by the operator.

In protecting the switch mechanism from access thereto by an operator from within the shaft, while at the same time facilitating the making of electrical connections of the system, I provide a housing formed of one integral casting provided with connecting chambers so formed as to permit free access to the electrical conduits connecting the different housings of a system and also to the switch mechanism proper, and the making of the electrical connections with the switch contacts, this housing being so formed as to avoid any possible short circuiting through the movement of the switch arm mounted in one of these chambers. Both chambers are preferably provided with

closure covers for the exclusion of dust, dirt and oil, and for preventing access to within the housing without the use of tools. The housing also has cast integrally therewith 5 securing means connected with the wall angle of the elevator guides, and a striker plate operative upon the actuating member controlled by the lock mechanism of the elevator door. By this construction permanency in the relation of various parts necessary to a reliable actuation of the interlock mechanism is secured, since under no circumstances can any of the parts of the interlock become so disarranged as to interfere 10 with a positive, certain operation of the interlock with each unlatching and latching of the lock upon the elevator door.

The invention consists in the novel features of construction and combination of 20 parts hereinafter set forth and described and more particularly pointed out in the claims hereto appended.

Referring to the drawings,

Fig. 1 is a view of one electrical interlock 25 mechanism of a system, and of fragmentary portions of an elevator door and its latch mechanism controlling the functioning of same, and of the rail structure for supporting the interlock; and

Fig. 2 is a section on the line 2—2 of 30 Fig. 1.

Like letters refer to like parts in both of said views.

In the embodiment of the invention shown 35 in the drawings, *a* indicates the upper section of a counterbalanced elevator door of the usual construction, and *b* the lower section thereof. The upper section carries the usual latch member *c* co-operating with a 40 striker member *d* constituting a part of the top bar structure of the lower section. At *e* are shown portions of the connecting means between the two door sections by which they are caused to have simultaneous movement 45 in opposite directions during the opening and closing of the door.

In the drawings, the invention is shown as applied to ordinary counterbalanced doors in which the two sections have movement in 50 the same vertical plane, but the invention may be applied in exactly the same manner to doors in which the sections have movement in parallel vertical planes, or in which they pass from one vertical plane to another 55 during the opening and closing movement.

The door sections *a* and *b* are mounted upon suitable guides *f* carried by what is known as a wall angle *g* which extends inwardly of the shaft. When electric interlocks 60 are used, the switch mechanism forming a part of the interlock is mounted upon the wall angle *g* in a position where the movable switch member will be actuated substantially simultaneously with the engagement of the latch member *c* with its

striker member *d*, thus permitting power to be applied to the elevator motor only after the door has been closed while at the same time interrupting the circuit to said motor substantially simultaneously with, or prior to, the initial opening movement of the doors.

My present invention relates more particularly to a construction of the switch mechanism by which it may be wired with greater facility, and the various parts of the mechanism will not be subject to likelihood of disarrangement from vibrations due to the repeated actuation of doors, imparting greater reliability or dependability to its functioning. At the same time, the construction of the switch mechanism is such as to cause the actuation of the latch member in either locking or unlocking the door to act positively upon the switch mechanism to cause the making and breaking of the circuit to be under the control of the latch member, the construction of the movable part of the switch, however, being such as to prevent the closing of the switch except under the control of said latch member.

The electric interlock of my invention includes a particular construction of housing for the switch mechanism proper, a particular construction of switch mechanism proper, and a particular construction of co-operating member actuated by the latch mechanism and co-operating with said housing and said switch mechanism.

The switch mechanism proper is within 100 a housing having a curved striker plate *h*, the curved surface of which is presented upwardly of the top, and having an opening therethrough at *h'* adjacent the bottom, of the housing. This housing has upper and lower nipples *i*—*i'* for the reception of the ends of ordinary electrical conduits *i*², said nipples including clamp members *i*³ and being interiorly shouldered at *i*⁴ to prevent relative movement of the housing and the fittings. This housing for convenience of expression may be considered as containing two chambers *h*² and *h*³, one of which as *h*² is offset with relation to the other to bring the conduits close to the wall of the shaft, and to permit convenient access thereto for the drawing of wires; to properly position the striker plate *h* with relation to the inner face of the door section and the member actuated by the latch mechanism of the door and co-operating with the switch mechanism, and to permit the convenient connection of the wires with the binding posts of the switch mechanism. The top and bottom walls of said housing are connected by a vertically extending partition *h*⁴ supporting the binding posts and the fixed contacts of the switch mechanism, this partition being of a width to afford an opening between the chambers *h*²—*h*³ suffi- 105 110 115 120 125 130

cient to permit convenient access from the chamber h^2 to the chamber h^3 when making the electrical connections.

The portion of the housing about the chamber h^3 extends from the portion forming the chamber h^2 a sufficient distance to afford ample space between the rear edge of the partition h^4 and the closed back of the housing (as shown more particularly in Fig. 2) to permit the convenient running of wires, and access to the chamber h^3 from both the back and front thereof.

The front of the housing is provided with extensions h^5 and h^6 extending above and below the top and the bottom respectively of the housing, by means of which the housing may be securely bolted to the wall angle g adjacent the edge of the flange thereof extending inwardly of the shaft, the striker member h being positioned inwardly of the shaft with relation to the said edge of said wall angle.

All parts of the housing h to h^6 and portions of the nipples $i-i'$ are made of a single integral casting, thus ensuring permanency in the relation of all of the parts of the housing.

The opening by which access may be had to the chamber h^2 and from said chamber to the chamber h^3 is closed by a cap j and the front of the chamber h^3 is closed by a cap j' thus protecting the wiring and switch mechanisms from dust, dirt and oil which accumulate rapidly about all parts of a rail structure of an elevator shaft.

The switch mechanism proper consists of two fixed contacts $k-k'$ also serving as binding posts by means of which the conductor wire m may be connected with one of said contacts, and the conductor wire m' may be connected with the other of said contacts. These contacts are mounted upon a block k^2 of insulating material, the means securing said contacts in position upon said plate being insulated by the strip k^3 from the partition h^4 to which the contacts are secured by means of the insulating block k^2 , by screws, or in any other desired manner.

Co-operating with the contacts $k-k'$ is a bridge contact plate n slidingly mounted upon an angular stem n' and acted upon by a spring n^2 , a pin n^3 limiting the action of said spring upon said stem n' . The stem n' is carried by a block of insulation o , the means of attachment of said stem and said block being protected by an insulating strip o' , said stem being secured to a switch arm p by means of the insulating block o , thus thoroughly insulating the plate n from said switch arm.

The switch arm p is overbalanced by means of the weight p' so as to have a normal tendency to move the bridge contact plate n out of engaging relation with the

fixed contacts $k-k'$. The normal action of the spring n^2 , when the movable contact is engaged with the fixed contacts, will be to assist the actions of this overbalancing weight or impart a starting impulse to the switch arm for separating the movable contact from the fixed contacts while ensuring a rubbing engagement of these parts, when making the circuit, in the manner herein-after referred to.

Slidably mounted upon the door section a , and pivotally connected with the latch member c is a member movable with said door and co-operating with the switch mechanism for controlling the circuit to the elevator motor, the wires $m-m'$ being a part of this circuit. This member, in the form of the invention shown, comprises a bolt q having a projection q' at the free end thereof, adapted to enter a recess or socket in the movable switch member p formed by an extension r at the bottom of said switch arm and an upwardly extending end r' carried by said extension. The construction of said projection q' , and the arrangement of said socket forming parts are such that these parts engage or interlock substantially simultaneously with the engagement of the bolt member q with the switch arm, so that the retraction of said bolt member will supplement the action of the spring n^2 , and of the overbalancing weight p' in moving the bridge contact member out of engaging relation with the fixed contacts $k-k'$, substantially simultaneously with, or immediately following, the release of the latch c , or during the initial opening movement of the door sections a and b .

The latch member c is acted upon by a suitable spring c' having a normal tendency not only to engage the latch member with its co-operating keeper, but to engage the member q with the switch arm p .

At s I have shown a guide strap for the member or bolt q , there being sufficient clearance to compensate for the slight arc of movement of said bolt, resulting from pivotal movement of the latch member c .

The operation of the herein described interlock is substantially as follows:—

In installing the interlock, the housing with the switch mechanism assembled therein is mounted by means of bolts to the inwardly directed flange of the wall angle, being so positioned as to have the opening through the striker plate h in accurate register with the member or bolt q , and the socket formed in the switch arm p in engaging relation with the projection q' . The conduits i^2 are then positioned in the nipples $i-i'$ provided therefor respectively, each of these conduits extending from the housing at one door opening to the housing at the adjacent door openings above and be-

low. The shoulders within the nipples $i-i'$ will prevent sliding movement of the conduits to within the chamber h^2 of any housing, these shoulders supplementing the 5 action of the clamps formed by the said nipples.

By this construction, since all of the switches are in series in the same circuit, it is apparent that short lengths of wire may 10 be used, thus avoiding all that delay and inconvenience incidental to drawing a wire throughout the entire length of the conduit and the various housings before making the electrical connections, and cutting and re- 15 adjusting the wire when making such connections. When these short lengths are used, the free ends of the wire may be conveniently brought by hand about the partition h^4 and connected with one or the other 20 of the binding posts formed by the contacts $k-k'$.

When a door is closed, the latch mechanism c , the switch arm p , and the member or bolt q , actuated from the latch member 25 and acting upon said switch arm will be in the positions shown in Fig. 1 of the drawings, the spring n^2 being tensioned through the pressure exerted upon the switch arm by the spring c' acting upon the latch 30 mechanism. When the parts are so positioned, it is to be noted that the projection q' is engaged with the upwardly extending end r' of the extension r .

When it is desired to open the door, the 35 latch is actuated by the operator to disengage its hooked end from the keeper d upon the door section b , the pivotal movement of the latch member in thus disengaging it from said keeper d drawing the bolt or member q away from the wall angle. This 40 movement of said member or bolt will not only permit the spring n^2 and the overbalancing weight p' to act to separate the bridge contact n from the fixed contacts $k-k'$, but will impart a positive movement 45 to said switch arm in the event that it does not move as rapidly as does the bolt q . The movement of the member or bolt q must occur before any opening movement can be 50 imparted to the door, or be complete by the time that the latch member c is disengaged from its keeper d .

The overbalancing weight p' will, through 55 the switch arm p , maintain the contact n out of engagement with the fixed contacts $k-k'$.

A door is closed by merely drawing down 60 the upper section, this movement, through the connecting means e , causing the lower section b to have an upward movement. As the end of the member or bolt reaches the opening through the striker h , which will be substantially simultaneously with the 65 passage of the hooked end of the latch through its keeper d , the spring c' acts si-

multaneously upon said latch member and said bolt q to engage the former with its keeper d and the latter with the switch arm p , and thus move the contact member n into engagement with the fixed contacts 70 $k-k'$. The quantity of this movement is greater than that required to simply engage the contact n with the contacts $k-k'$, thus causing, by reason of the arc described by the switch arm p and the stem n' carried thereby, to impart a vertical sliding movement to the plate n while engaging said fixed contacts. This rubbing contact will ensure a desired intimate engagement 75 between the movable and the fixed contacts thus effectively closing the circuit through said switch mechanism, it being understood that all other switch mechanisms in the shaft must be likewise closed in order to permit the application of power to the elevator. When engaging the switch arm p , the projection q' of the member or bolt q will enter the socket formed by the extension r and projecting end r' , so that the bolt cannot be withdrawn from its engaging 80 relation with the switch arm without moving the contact plate n out of engaging relation with the fixed contacts $k-k'$.

The interlocking of the member or bolt q with the switch arm p in the manner described not only ensures the opening of the 85 circuit prior to, or simultaneously with, the initial opening movement of the door, but prevents the blocking of the switch arm in a manner to cause it to operate independently of the door, or to remain closed, notwithstanding that the member or bolt q has been retracted and the door opened. In fact, this construction prevents any tampering with the switch mechanism which 90 would result in a condition permitting doors to remain open and the elevator to be operated nevertheless.

The offsetting of the two chambers h^2-h^3 with relation to each other, not only brings 95 the striker h inwardly of the shaft in the proper position with relation to the plane of movement of the member q , but positions the conduits i^2 so as to afford ample space 100 for the handling of the ends of the wires, and their convenient passage to the chamber h^3 and connection with the binding posts upon the contacts $k-k'$.

It is not my intention to limit the invention to the precise details of construction shown in the drawings, it being apparent that such may be varied without departing from the spirit and scope of the invention.

Having described the invention, what I 110 claim as new and desire to have protected by Letters Patent, is:—

1. An electric interlock for elevator doors embodying therein the combination with a 115 vertically movable door section, a spring 120

- actuated latch mechanism carried thereby, and a guide structure for said section including a wall angle, of a housing secured to said wall angle having an opening therethrough adapted to permit the passage of a bolt, and a striker plate adapted to guide the bolt to said opening, an electrical switch mechanism in said housing embodying therein co-operating fixed and movable contact members, and a movable member projecting across the opening in said housing, said contacts being arranged in circuit with the motor for actuating an elevator car, a bolt operatively connected with said latch mechanism and adapted to pass through said opening and engage said movable member when the door section is in the closed position, a socket forming projection upon said movable member and projecting through the opening in said housing into engaging relation with said bolt, and a projection upon said bolt adapted to enter and interlock with said socket, whereby said switch mechanism will be positively actuated to both close and open the circuit in which it is arranged substantially simultaneously with the setting and the release of said latch mechanism, with the closing, or preparatory to the opening, of the door section.
2. An electric interlock for elevator doors embodying therein the combination with a door structure comprising two door sections having simultaneous vertical movement in opposite directions when opening and closing the door, a spring actuated latch mechanism carried by one of said sections, and a guide structure for said sections including a wall angle, of a housing secured to said wall angle at substantially the meeting point of said door sections having an opening therethrough adapted to permit the passage of a bolt, and a striker plate adapted to guide the bolt to said opening, an electrical switch mechanism in said housing embodying therein co-operating fixed and movable contact members, and a movable member projecting across the opening in said housing, said contacts being arranged in circuit with the motor for actuating an elevator car, a bolt operatively connected with said latch mechanism and adapted to pass through said opening and engage said movable member when the door sections are in the closed position, a socket forming projection upon said movable member and projecting through the opening in said housing into engaging relation with said bolt, and a projection upon said bolt adapted to enter and interlock with said socket, whereby said switch mechanism will be positively actuated to both close and open the circuit in which it is arranged substantially simultaneously with the setting and the release of said latch mechanism with the closing, or preparatory to the opening, of the door section.
3. An electric interlock for elevator doors embodying therein the combination with a vertically movable door section, a spring actuated latch mechanism carried thereby, and a guide structure for said section including a wall angle, of a housing secured to said wall angle having an opening therethrough adapted to permit the passage of a bolt, and a striker plate adapted to guide the bolt to said opening, an electrical switch mechanism in said housing arranged in circuit with the motor for actuating an elevator car, said switch mechanism including a movable switch arm having socket-forming means projecting through said opening in said housing and beyond said striker plate, and a bolt operatively connected with said latch mechanism and adapted to pass through said opening in said housing and engage said switch arm when the door section is in the closed position, said bolt having a projection adapted to interlock with said socket-forming means upon said movable switch arm when the door section is in the closed position, whereby said switch mechanism will be positively actuated to both close and open the circuit in which it is arranged substantially simultaneously with the setting and the release of said latch mechanism with the closing, or preparatory to the opening, of the door section.
4. An electric interlock for elevator doors embodying therein the combination with a door structure comprising two door sections having a simultaneous vertical movement in opposite directions when opening and closing the door, a spring actuated latch mechanism carried by one of said sections, and a guide structure for said sections including a wall angle, of a housing secured to said wall angle at substantially the meeting point of said door sections having an opening therethrough adapted to permit the passage of a bolt, and a striker plate adapted to guide the bolt to said opening, an electrical switch mechanism in said housing arranged in circuit with the motor for actuating an elevator car, said switch mechanism including a movable switch arm having socket-forming means projecting through said opening in said housing and beyond said striker plate, and a bolt operatively connected with said latch mechanism and adapted to pass through said opening and engage said switch arm when the door section is in the closed position, said bolt having a projection adapted to interlock with said socket-forming means upon said movable switch arm when the door section is in the closed position, whereby said switch mechanism will be positively actuated to both close and open the circuit in which it is arranged substantially simultaneously with the setting and the release of said latch mechanism with the closing, or preparatory to the opening, of the door section.

6
ting and the release of said latch mechanism with the closing, or preparatory to the opening, of the door section.

5. An electric interlock for elevator doors embodying therein the combination with a vertically movable door section, a spring actuated latch mechanism carried thereby, and a guide structure for said section including a wall angle, of a housing secured to said wall angle having an opening therethrough adapted to permit the passage of a bolt, and a striker plate adapted to guide the bolt to said opening, an electrical switch mechanism in said housing arranged in circuit with the motor for actuating an elevator car, said switch mechanism including spaced fixed contacts within said housing, a pivoted switch arm, a stem carried by said switch arm, a bridge contact slidably mounted upon said stem, a spring acting to normally thrust said bridge contact towards said fixed contacts, an overbalancing weight operative upon said switch arm to normally maintain said bridge contact out of engagement with said fixed contacts, a socket forming projection upon said switch arm projecting through the opening in said housing into engaging relation with a bolt, and a bolt operatively connected with said latch mechanism and adapted to pass through said opening and engage said switch arm when the door section is in the closed position, said bolt having a projection adapted to interlock with said socket-forming projection upon said movable switch arm when the door section is in the closed position, whereby said switch mechanism will be positively actuated to both close and open the circuit in which it is arranged substantially simultaneously with the setting and the release of said latch mechanism with the closing, or preparatory to the opening, of the door section.

45. An electric interlock for elevator doors embodying therein the combination with a vertically movable door section, a spring actuated latch mechanism carried thereby, and a guide structure for said section including a wall angle, of a housing secured to said wall angle, having an opening therethrough adapted to permit the passage of a bolt, two connected chambers, one of which is offset toward the wall of the elevator shaft with relation to the other, a striker plate adapted to guide the bolt to said opening, and a partition partially closing the chamber inwardly of the shaft, spaced fixed contacts carried by and insulated from said partition, a movable switch arm mounted in said chamber adjacent said partition and projecting across the opening in said housing, a bridge contact carried by said switch arm and adapted to co-operate with said fixed contacts to make or break the circuit to the motor for the elevator car, a bolt operatively connected with said latch mechanism and adapted to engage said switch arm and close said switch mechanism when the door section is in the closed position, means operative upon said switch arm whereby the bridge contact will be maintained out of engagement with said fixed contacts when said bolt is withdrawn from engagement with said arm while the door is open, and removable closure caps for said chambers respectively.

60. An electric interlock for elevator doors operatively connected with said latch mechanism and adapted to pass through said opening in said housing and engage said switch arm when the door section is in the closed position, means operative upon said switch arm whereby the bridge contact will be maintained out of engagement with said fixed contacts when said bolt is withdrawn from engagement with said arm while the door is open, a socket forming projection upon said switch arm projecting through the opening in said housing into engaging relation with said bolt, and a projection upon said bolt adapted to enter and interlock with said socket, whereby said switch mechanism will be positively actuated to open the circuit in which it is arranged substantially simultaneously with the setting and the release of said latch mechanism with the closing, or preparatory to the opening, of the door section.

65. An electric interlock for elevator doors embodying therein the combination with a vertically movable door section, a spring actuated latch mechanism carried thereby, and a guide structure for said section including a wall angle, of a housing secured to said wall angle, having two connected chambers, one of which is offset toward the wall of the elevator shaft with relation to the other, conduit nipples leading from said chamber positioned toward the wall of the elevator shaft, a partition partially closing the chamber inwardly of the shaft, spaced fixed contacts carried by and insulated from said partition, a movable switch arm mounted in said chamber adjacent said partition, a bridge contact carried by said switch arm and adapted to co-operate with said fixed contacts to make or break the circuit to the motor for the elevator car, a bolt operatively connected with said latch mechanism and adapted to engage said switch arm and close said switch mechanism when the door section is in the closed position, means operative upon said switch arm whereby the bridge contact will be maintained out of engagement with said fixed contacts when said bolt is withdrawn from engagement with said arm while the door is open, and removable closure caps for said chambers respectively.

70. An electric interlock for elevator doors embodying therein the combination with a vertically movable door section, a spring actuated latch mechanism carried thereby, and a guide structure for said section including a wall angle, of a housing secured to said wall angle, having two connected chambers, one of which is offset toward the wall of the elevator shaft with relation to the other, a partition partially closing the chamber inwardly of the shaft, spaced fixed contacts carried by and insulated from said partition, a movable switch arm mounted in said chamber adjacent said partition and

110

115

120

125

130

ber adjacent said partition, a bridge contact carried by said switch arm and adapted to co-operate with said fixed contacts to make or break the circuit to the motor for the elevator car, a bolt operatively connected with said latch mechanism and adapted to engage said switch arm and close said switch mechanism when the door section is in the closed position, a striker member having an opening therethrough adapted to permit the passage of said bolt into or out of engaging relation with said switch arm and formed integrally with other portions of said housing, and means operative upon said switch arm whereby the bridge contact will be maintained out of engagement with said fixed contacts when said bolt is withdrawn from engagement with said arm while the door is open.

20 9. An electric interlock for elevator doors embodying therein the combination with a vertically movable door section, a spring actuated latch mechanism carried thereby, and a guide structure for said section including 25 a wall angle, of a housing secured to said wall angle, having two connected chambers, one of which is offset toward the wall of the elevator shaft with relation to the other, a partition partially closing the chamber inwardly of the shaft, spaced fixed contacts carried by and insulated from said partition, 30 a movable switch arm mounted in said

chamber adjacent said partition, a pivoted switch arm mounted in said chamber adjacent said partition, a stem carried by said switch arm, a bridge contact slidably mounted upon said stem, a spring acting to normally thrust said bridge contact towards said fixed contacts, an overbalancing weight operative upon said switch arm to normally 35 maintain said bridge contact out of engagement with said fixed contacts, a bolt operatively connected with said latch mechanism and adapted to engage said switch arm and close said switch mechanism when the door 40 section is in the closed position, and a striker member having an opening therethrough adapted to permit the passage of said bolt into or out of engaging relation with said switch arm and formed integrally with other 45 portions of said housing, said bolt having a projection adapted to interlock with said socket-forming means upon said movable switch arm when the door section is in the closed position, whereby said switch mechanism will be positively actuated to open the circuit in which it is arranged substantially 50 simultaneously with the release of said latch mechanism preparatory to the opening of the door section.

In witness whereof I have hereunto affixed my signature this 7th day of April, 1925.

ROBERT S. PEELLE.
